[57] CLAIM

The ornamental design for an exterior body panel kit for attachment to a truck body, as shown and described.

DESCRIPTION

FIG. 1 is a front, top and left side perspective view of an exterior body panel kit for attachment to a truck body showing my new design, the right side of the design being a mirror image of the left side shown in FIG. 1; FIG. 2 is a rear, top and left side perspective view of the left rear fender extension thereof shown separately for clarity of illustration;

FIG. 3 is a top, rear and right side perspective view of the front air dam thereof shown separately for clarity of illustration;

FIG. 4 is a top plan view thereof; and,

FIG. 5 is a bottom plan view thereof.

FIG.4

FIG. 5
